UNITED STATES PATENT OFFICE.

CLARK J. BROWN, OF PLYMOUTH, NEW HAMPSHIRE.

IMPROVEMENT IN SAFETY APPARATUS FOR LAMPS.

Specification forming part of Letters Patent No. 135,074, dated January 21, 1873.

To all whom it may concern:

Be it known that I, CLARK J. BROWN, of Plymouth, of the county of Grafton and State of New Hampshire, have invented a new and useful Safety Apparatus to be used in supplying a lamp with oil or fluid from a can; and I do hereby declare the same to be fully described in the following specification and represented in the accompanying drawing, of which—

Figure is a top view; Fig. 2, a side elevation; and Fig. 3, a longitudinal section of it. Fig. 4 is a side view of it as applied to an oil-can.

In such drawing, A denotes a common liquor-funnel provided with a bail, B, formed and having a hook, a, as shown, the bail being arranged on and pivoted to one side of the funnel, in manner as represented. Extending through the funnel and above it and fastened to its inner surface is a tube, C, from whose upper end a flexible tube, D, is projected to another tube, E, going axially through a cork or stopper, F, the tubes C and E being inserted air-tight within the flexible tube D.

In using the apparatus the stopper or cork is to be inserted in the mouth-piece b of the can G, the hook of the bail being extended in-

to the nose c, and the discharge-tube or educt d of the funnel being inserted in the filling-orifice of the lamp-reservoir.

The hooked bail serves as a rest to support and steady the can while it may be in the act of being tipped for supplying the lamp with fluid. It also enables a person to see to advantage the fluid while flowing from the nose of the can. Furthermore, the tubes C, D, and E not only admit air from the lamp into the can, in order that the fluid may freely flow from the latter, but with the cork they insulate any combustible vapor in the can from the flame of the lamp, and thereby prevent accidental explosion of such vapor.

I claim as my invention as follows, viz:

1. The combination of the flexible tube D and the stationary tubes C E with the funnel A and cork or stopper F.
2. Also, the combination of the hooked bail B, or its equivalent, the funnel A, the cork F, and the stationary and flexible tubes C D E, all arranged substantially as and for use as specified.

CLARK J. BROWN.
